UNITED STATES PATENT OFFICE

1,963,063

STRIP SCRUBBING MACHINE

Harry S. Schutte, Gary, Ind., assignor to American Sheet and Tin Plate Company, a corporation of New Jersey

Application September 21, 1932, Serial No. 634,238

2 Claims. (Cl. 15—77)

This invention relates to a machine for scrubbing continuously moving wide metal strip free from foreign matter acquired during its manufacture or otherwise.

5 The object is to construct such a machine to use a cleansing fluid without incidentally contaminating the freshly cleaned strip therewith, to include a casing in which a section of the strip is held by simplified means and containing 10 sundry cleaning and/or drying apparatus and, further, the provision of means for preventing condensate formed in this casing from wetting the exiting strip. Further objects not included 15 in this necessarily brief recital may be inferred from the following disclosure of an example of the invention.

Referring to the drawing:

Figure 1 is a side elevation of a strip scrubbing machine constructed according to the invention.

Figure 2 is a cross-section from the line II—II in Figure 1.

Figure 3 is a partial end elevation of Figure 2.

The metal strip 1 leaves a washing tank 2, is 25 guided upwardly in its moving direction by a large roller 3 and then horizontally to a stand of pulling pinch-rolls 4.

A stand of scrubbing rolls 5 is positioned so that the upwardly directed strip passes therethrough. 30 These scrubbing rolls may be cylindrical bristle brushes and suitably supported by a housing 6 carrying roll pressure applying means 7. They are belted to a motor 8 for rotation in an opposite direction to that of the strip. This not only 35 assures greater scrubbing action but, by suitably regulating their rotating speed, serves to maintain the strip taut to the pinch-rolls 4.

Nozzles 9 extend the width of the strip and are 40 constructed to throw jets of water or other fluid into the upper nip of the scrubbing rolls 5. Preferably, the volume of this water is sufficient to create a fluid stream which runs down the strip 1 and into the tank 2. This carries all of the removed contamination away from the cleaned 45 strip, as well as the dirty water.

A casing 10 is constructed to cover the horizontal portion of the strip and is provided with an open end 11 forming an entrance and a narrow slot 12 forming an exit. This casing may 50 house a second stand of scrubbing rolls 13 which may be constructed similarly to the ones described. These are preferably also belted to the motor 8 for rotation in an opposite direction to that of the moving strip. They must not, however, rotate with sufficient speed to loosen the

strip between them and the first stand. While the rolls 13 are not absolutely necessary, their use is preferable as a precautionary measure for the removal of anything the first stand might miss.

The casing also contains a number of different length nozzle members 14 which are arranged to eject water jets on both sides of the strip just as it leaves the second stand of scrubbing rolls 13. These are selectively connected to a hot water tank 15 through valves 16.

In the present instance hot water is furnished the tank 15 by a conventional steam siphon heating arrangement 17. Other means for keeping the water hot in the tank 15 might obviously be substituted.

The nozzle members 14 are provided in different lengths so that they may accommodate different strip widths. The valves 16 are operated to connect the nozzle members closest the strip width being cleansed, with the hot water tank 16. They are constructed to throw sufficient hot water on the strip to raise its temperature so that its drying is effected by evaporation.

Just beyond the nozzle members 14 and in the casing 10 is arranged an idling stand of squeezer rolls 18 which serve to remove the greater part of the hot water from the strip. These squeezer rolls are not indicated in detail, because they may be constructed in a number of ways. For instance, they may consist of a pair of resilient rubber rolls with idle shafts, and pressed against the metal strip by suitable apparatus.

The metal strip leaves the exit 12 of the casing 10 in a dry state and passes through the pulling pinch-rolls 4 onto other apparatus. Because of the steam and moisture in the casing 10 resulting from the hot water application and subsequent evaporation, there is danger of condensate running down the vertical wall above the exit 12 and dropping on the dried strip. This is effectively prevented by a small trough or gutter 19 which runs the width of the exit 12 above the strip. This catches any such condensate and prevents it wetting the exiting strip.

While I have shown and described one specific embodiment of my invention in accordance with the patent statutes it will be understood that I do not wish to be limited thereto, since various modifications may be made without departing from the scope of my invention as defined in the following claims.

I claim:

1. A machine for scrubbing continuously mov-

ing wide metal strip including the combination of a casing having an entrance and exit for the moving strip, means for scrubbing said strip, means in said casing for drying said strip and 5 a trough or gutter constructed and arranged over the strip passing through said exit to catch condensate forming on the inside of said casing.

2. A machine for scrubbing continuously moving wide metal strip including means for directing the strip upwardly in its moving direction and then horizontally, a stand of scrubbing rolls through which said strip passes while moving in its upward direction, a stand of pinch-rolls for pulling the horizontally directed strip portion, 10 means for rotating said scrubbing rolls oppositely to the strip's moving direction, nozzles con-

structed and arranged to eject sufficient fluid into the upper nip of said scrubbing rolls on both sides of the strip to produce a downwardly moving flow, a casing having an entrance and exit for the horizontally directed strip, a plurality of different length fluid ejecting means right angularly arranged on both sides of the strip in said casing, means for selectively supplying said fluid ejecting means with heated fluid, means for removing excess fluid from both sides of said strip arranged between said different length fluid ejecting means and the exit of said casing, and a trough or gutter constructed and arranged over said exit and strip to catch condensate formed on the inside of said casing.
